(57) **CLAIM**

The ornamental design for a cleaning fluid tank, as shown and described.

DESCRIPTION

FIG. 1 is a perspective view of a first embodiment of a cleaning fluid tank showing our new design;

FIG. 2 is a front view of the cleaning fluid tank of FIG. 1; FIG. 3 is a rear view of the cleaning fluid tank of FIG. 1; FIG. 4 is a left side view of the cleaning fluid tank of FIG. 1;

FIG. 5 is a right side view of the cleaning fluid tank of FIG. 1;

FIG. 6 is a top view of the cleaning fluid tank of FIG. 1; FIG. 7 is a bottom view of the cleaning fluid tank of FIG. 1;

FIG. 8 is a perspective view of a second embodiment of a cleaning fluid tank showing our new design;

FIG. 9 is a front view of the cleaning fluid tank of FIG. 8; FIG. 10 is a rear view of the cleaning fluid tank of FIG. 8;

FIG. 11 is a left side view of the cleaning fluid tank of FIG. 8; FIG. 12 is a right side view of the cleaning fluid tank of FIG. 8;

FIG. 13 is a top view of the cleaning fluid tank of FIG. 8; and,

FIG. 14 is a bottom view of the cleaning fluid tank of FIG. 8.

The broken lines in the drawings show portions of the cleaning fluid tank that form no part of the claimed design.

1 Claim, 14 Drawing Sheets
